(74) Attorney, Agent, or Firm—Sheldon & Mak; Danton K. Mak

(57) CLAIM

A design for a portion of a shoe outsole, as shown and described.

DESCRIPTION

FIG. 1 is a perspective view of a portion of a shoe outsole showing my new design; and,

FIG. 2 is a bottom plan view thereof.

The broken lines shown for the remainder of the sole and the shoe are for illustrative purposes only, and form no part of the claimed design.
